Primary Examiner — John R Yeh*Assistant Examiner* — Dustin Andrew Griffith(74) *Attorney, Agent, or Firm* — Kane Kessler, P.C.; Paul E. Szabo(57) **CLAIM**

The ornamental design for a holster as shown and described.

DESCRIPTION

FIG. 1 is a face side perspective view of the holster showing our new design;

FIG. 2 is a body side perspective view thereof;

FIG. 3 is a face side elevational view thereof;

FIG. 4 is a body side elevational view thereof;

FIG. 5 is a bottom plan view thereof;

FIG. 6 is a top plan view thereof;

FIG. 7 is an end view thereof; and,

FIG. 8 is the opposite end view thereof.

The dash-dash broken lines are for purposes of depicting portions of the holster that are unclaimed subject matter and form no part of the claimed design. The long dash-short dash broken lines are for purposes of indicating the boundary between claimed subject matter and unclaimed subject matter and form no part of the claimed design.
